COVER FOR BARRELS OR THE LIKE

Llewellyn W. Evans, Richmond, Calif., assignor
to Paragon Metal Container Company, Contra
Costa County, Calif., a corporation of Calif-
ornia

Application April 20, 1931. Serial No. 531,307

6 Claims. (Cl. 220—57)

The invention relates to covers, usually made of metal, for closing the open end of barrels, drums, and similar metal containers, and relates in its present embodiment to a metal cover for closing the usual opening in the top of such barrels.

An object of the invention is to provide a cover of the character described having means for placing the cover into or releasing it from locked and sealed engagement with the barrel, which in the operative position of the cover lies concealed thereunder, but may be readily operated from the exterior thereof both for locking and releasing purposes while the cover is engaged in the opening.

Another object of the invention is to provide a cover of the character described in which no part thereof will protrude beyond the end of the barrel when the cover effects a full closure of the barrel.

A further object of the invention is to provide a cover of the character described in which but a single displaceable part is exposed on the cover when the latter is in fully closed position over the barrel opening.

A still further object of the invention is to provide a cover of the character described in which the locking and releasing means, while carried on the under side of the cover, may be in part temporarily moved to the exposed side of the cover for facilitating the actuation of said means.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is an underneath view of the cover showing the latter operatively locked to the barrel end.

Figure 2 is a view similar to Figure 1 but showing the cover released.

Figure 3 is a longitudinal sectional view of the cover showing it operatively held in position, the line of the section being indicated by the line 3—3 of Figure 1.

Figure 4 is a view similar to Figure 3, but showing the cover released and partially dis- placed in the barrel opening, the plane of the

section being generally indicated by the line 4—4 of Figure 2.

Figure 5 is a fragmentary transverse sectional view of the cover taken on the line 5—5 of Figure 1.

Figure 6 is a plan view of the barrel with the cover operatively secured thereto, but with the center cap removed.

Figures 7 and 8 are sectional views similar to Figure 1 but showing modified constructions.

Figure 9 is an enlarged fragmentary view of a portion of the parts shown in Figure 8.

As illustrated in the drawings, the cover of my invention is arranged for use with a type of metal barrel or drum 5 having one end wall 6, preferably the top, formed with a marginal rolled bead 7 which defines the main opening 8 of the barrel. The cover, as clearly shown in Figures 3 and 4, comprises a closure plate 9 provided with a peripheral recessed portion 11 containing a resilient gasket 12 which is adapted to seat upon the bead 7 when the cover is operatively disposed over the barrel opening. It is to be noted that in the present instance the bead 7 is annular, and in conformity therewith the recessed portion 11 and gasket 12 are similarly formed. Also the wall 6 is spaced sufficiently inward from the end of the barrel so that the plate, including the portion 11, will lie within the sides of the barrel when the cover is operatively disposed over the opening.

Means are provided on the cover for forcing and holding the same onto the end wall when the cover is operatively positioned over the opening whereby the cover may be locked to the barrel with a sealed joint therebetween. Positioned on the under side of the plate and slidably carried on guides 14 affixed to the plate adjacent the outer edge thereof, are a plurality of arms or bolts 15 which are arranged to be moved substantially radially of the cover into or out of engagement with the under side 17 of the wall 6. Movement of the arms is controlled

by means of an actuator member 18 which as here shown is mounted for rotation on a cylindrical flange 19 depending centrally from the plate. Each of the arms is pivotally connected at the inner end of the member 18 so that upon rotation of the latter the arms may be retracted to lie within the outer edges of the plate as shown in Figure 2, or they may be extended to engage the end wall 6 as indicated in Figure 1. It will be clear that when the arms are in the former position the cover may be readily removed from or replaced over the opening.

whereas when the arms are extended and engaged under the wall 7 the cover will be locked to the barrel. It will be noted that when the cover is engaged in the opening, the plate will lie substantially coplanar with the end wall, and the arms are so positioned that when engaged with such wall the gasket will be compressed against the head whereby a sealed joint may be provided. Preferably in moving the actuator member to engage the end wall, when the arms are retracted, the member is rotated sufficiently to move the connecting point of the arms therewith to a position beyond the line intersecting such point and the point at which the arm is slidably connected to the plate at its outer end. In this manner with the engagement of the arms and end wall such as to resiliently resist retraction of the arms, the latter will become automatically locked in extended position and retractable only upon reverse rotation of the actuator. Movement of actuator in both directions of rotation is preferably limited by engagement of the side edges of the arms with the angularly related sides of the bearing members 14.

In order to facilitate the ready engagement of the arms with the wall 6, the outer ends of such arms are beveled on their upper sides. It is to be noted that an extremely light and simple but strong construction is provided by the design of the parts as here shown. For instance the arms are formed of sheet metal bent to channel form as illustrated in Figure 5. Also the actuator member is stamped in one piece and pivotal attachment thereof to the arms is effected by rivets formed as a part of the member and secured to the body portion of the arm channel.

As the means on the cover for engaging or releasing the wall 6 is located entirely on the under side of the plate, the exposed side of the cover need have practically no moving parts, nor parts protruding beyond the end of the barrel. In this manner, even when the covers are operatively held on the barrels, the latter may be piled end to end, as in shipping or for storage, in compact and uniform formation. It will be evident, however, that in view of the concealed positioning of said means, including the actuator member, proper access should be had to such actuator for effecting the rotation thereof from the exposed side of the cover when the latter is operatively disposed in the opening. In accordance therefore, means are provided for affording such access. Formed in the plate at the central portion thereof, and in concentric relation to the actuator, is a hole 21 across the bottom of which extends a portion 22 of the actuator. The hole 21 is threaded for engagement with a plug 23 which may be screwed into or out of the hole from the exterior of the cover. It will be clear that when the plug is removed access may be had to the actuator so that by applying a proper tool thereto rotation thereof may be effected. Means are provided, however, whereby an associated part of the actuator may be temporarily projected through the hole 21 and above the cover so that rotation of the actuator may be accomplished by merely applying a wrench or other suitable tool to the top of the cover. Mounted in the actuator for rotation therewith at the center of turning thereof is what may conveniently be termed a gripping element 24 which may be moved axially of the actuator member and through the hole 21. By means of

stops 26 and 27 provided on the member 24, the latter may assume the normal depressed position shown in Figure 3 or the elevated position shown in Figure 4. With the member 24 in the first mentioned position, the plug 23 80 may be operatively engaged in the hole to seal the same, but in order to allow the gripping member to be raised to its elevated position the plug should be removed.

The operation of the closure is as follows: 85 Assuming the barrel is to be closed, the cover, with the arms in retracted position, is primarily set into the barrel opening so that the gasket rests on the bead. The plug if it is in the hole, is removed, and the gripping element raised to 90 elevated position with the operator's fingers or in any other suitable manner. Then with the element so positioned, a wrench or other appropriate tool is applied thereto at the top of the cover and rotated to force the arms into 95 engagement with the end plate. When the arms have been sufficiently extended to effect the seal between the cover and plate, the wrench or tool is removed from the gripping element whereby the latter will drop to its depressed position and 100 the plug screwed into place. With the parts thus positioned, the barrel opening will be effectively closed and the cover securely held in place under all conditions. To now release the cover it is merely necessary to remove the plug, 105 raise the gripping element and then apply the tool or wrench thereto to retract the arms.

In Figure 7 I have shown a slightly modified form of the invention. In this embodiment the gripping element 24 is omitted, the necessary 110 rotation of the actuator member being arranged to be effected by means of a tool such as the lever 31 which is insertable through the plate hole 21 from the exterior of the cover and releasably engageable with said member to 115 rotate same. A simple form of releasable connection between the lever and actuator is afforded by providing a poly-sided end portion 32 on the lever, which is engageable in a correspondingly shaped socket or opening 33 provided in the portion of the actuator visible through the hole 21. The advantage of the arrangement of this embodiment over the first described, is that the necessity of manipulating the gripping element 24 is dispensed with, but 120 on the other hand a more or less special tool is required for effecting the rotation of the actuator member.

In the embodiment shown in Figures 8 and 9, the gripping element 41 is not only unitarily 130 included with the actuator, but is designed to have the upper portion 42 thereof permanently extending above the cover plate. The element as here shown is mounted for rotation at the center of the cover plate with its lower end engaged with the actuator member for rotation therewith. The element is held in the cover by means of a flange 43 engaging the lower face of the actuator and a nut 44 which is positioned on the outer side of the plate and engages the threaded portion 46 of the element. By tightening the nut, gaskets 47 and 48 positioned on opposite sides of the plate, are compressed to seal the plate hole through which the element extends. In the use of the element the 145 nut is loosened so that the element may be easily rotated, the rotation being effected by inserting a bar in the forked end of the element. With this type of construction the need for the cap 23 is dispensed with, and at the same time 150

the actuator is at all times accessible on the exposed side of the cover.

I claim:

1. A cover for closing an opening in a barrel end or the like, comprising a plate having a hole and arranged to engage said opening on the exposed side of said end, means carried by said plate on the inner side thereof engageable with an inner side portion of the barrel to operatively hold the plate in said opening, means associated with said first means and accessible at said hole from the outer side of said plate to move said first means into or out of operative engagement with said barrel portion, and a releasable closure for said hole having a threaded engagement with said plate.

2. A cover for closing an opening in a barrel end or the like, comprising a plate having a hole and arranged to engage said opening on the exterior of the barrel, means carried by said plate on the inner side thereof engageable with the end at sides of the opening to operatively draw and hold the plate against said end, an engaging element for said means positionable in said hole, and a releasable closure for sealing said hole and rendering said element inaccessible.

3. In a cover for closing an opening in a barrel end or the like comprising a closure plate having a centrally disposed hole and arranged to engage over said opening on the outer side of said end, means carried by said plate on the inner side thereof extendible to engage the inner side of said end to draw and hold the plate against the end in operative position over said opening, a gripping member connected to said means to facilitate the actuation thereof from the exterior of said plate and being movable through said hole from the inner to the outer side of the plate, and a plug for sealing said hole with said member in position on the inner side of the plate.

4. In a cover for closing an opening in a barrel end or the like comprising a closure plate having a centrally disposed hole and arranged to engage the sides of said opening on the upper side of said end, a plurality of arms carried for movement by said plate on the underside thereof, an actuating member connected to said arms and operable to extend same outwardly to engage the under side of said end and thereby draw and hold said plate in sealing en-

gagement over said opening, a plug to seal said hole on the upper side of the end, and a gripping member associated with said actuating member and movable through said hole whereby in one position it will extend from the latter at the upper side of the end and in another position it will be retracted thereinto to permit the engagement of the plug therein.

5. In a cover for closing an opening in a barrel end or the like comprising a closure plate having a centrally disposed hole and arranged to engage the sides of the opening on the upper side of said end, a plurality of substantially radially movable arms slidably held on the under side of the plate and extendible to engage the under side of the end, a rotatable actuator member pivotally connected to said arms and carried by the plate in substantially concentric relation to said hole, a gripping member carried by said actuator member for positioning in and movement through said hole and arranged in one position to extend from said hole at the upper side of said end and in another position retracted into the hole, and a plug engageable in and arranged to close said hole in the last mentioned position of said gripping member.

6. In a cover for closing an opening in a metal barrel end having a rolled marginal edge portion defining said opening, comprising a closure plate having a centrally disposed hole and a gasket carried edge arranged to sealingly engage said edge, a plurality of substantially radially disposed arms on the under side of said plate, guides on said plate for slidably supporting said arms adjacent the edge of said plate, an actuating member rotatably carried by said plate in substantially concentric relation to said hole and pivotally connected to the inner end of each of said arms whereby on rotation of said member said arms will be extended or retracted to engage or release the under side of said end, a gripping member carried by said actuator member for positioning in and movement through said hole and arranged in one position to extend outwardly from said hole at the upper side of said end and in another position relatively retracted, and a screw-plug engageable in said hole to close same in the last mentioned position of the gripping member.
